UNITED STATES PATENT OFFICE

WILLIAM A. DEXTER, OF GLASGOW, SCOTLAND.

SURFACE CONDENSER INSTALLATION.

Application filed December 4, 1923. Serial No. 678,387.

To all whom it may concern:

Be it known that I, WILLIAM ALLINSON DEXTER, a subject of the King of Great Britain and Northern Ireland, and residing at 5 Glasgow, Scotland, have invented a certain new and useful Improvement in Surface Condenser Installations, of which the following is a specification.

This invention relates to surface condenser installations having provision for maintaining a constant load on the condensate pump.

Such installations usually include a collecting box or chamber located below the 10 main condenser for the reception of condensate from the main condenser and a centrifugal condensate pump connected on its suction side to the collecting box and on its discharge side to an overhead tank connected 15 directly to the feed heater, and, by an equalizing pipe, to the collecting box.

Heretofore the overhead tank has been, of necessity, located at a considerable elevation, usually higher than the ejector air pump 20 provided in such installations.

In the installation of the invention according to a preferred embodiment the "overhead" tank is formed as a sealed chamber from which a connection is taken directly to 25 the feed heater and through the feed heater to the feed supply (feed pump or feed tank) so that the condensate pump serves to create an artificial head and that the feed heater and the feed pump or the feed tank may be situated conveniently without necessity for providing a substantial static head.

There is desirably incorporated in the connection from the "overhead" tank to the feed heater a measuring device which serves 30 to measure the total quantity of condensate passing to the feed heater, so that, when it is desired to ascertain the quantity of steam condensed in the condenser, it is merely requisite to subtract from the quantity measured by the meter the calculated quantity of steam used in operating the stages of the 35 ejector air pump.

The invention is illustrated in the accompanying drawing in which Fig. 1 is a diagram of an installation including a sealed "overhead" tank. Fig. 2 is a sectional detail view of the ejector air pump.

Referring to Figs. 1 and 2, 1 denotes the main condenser below which is located a col-

lecting box or chamber 2 connected to the 55 main condenser and serving for the reception of condensate from the condenser. The centrifugal condensate pump 3 is connected on its suction side by the pipe 3' to the collecting box 2 and on its discharge side by a 60 discharge pipe 4 to an overhead tank 5. The tank 5 is connected to the feed heater 6 by piping 7 and to the collecting box 2 by an equalizing pipe 8, the flow of water from 65 the tank 5 to the box 2 being automatically regulated by a valve 9 controlled by a float 9'. The function of the pipe 8 is to return a controlled quantity of water from the tank 5 to the box 2 so as to maintain a constant 70 level in the box 2 and consequently a constant load on the condensate pump 3; the quantity of water passing through the piping 7 represents the difference between the quantity discharged by the pump 3 through the 75 pipe 4 and the quantity returned from the tank 5 to the box 2 through the pipe 8, being equal to the quantity of water entering the box 2 from the condenser 1, plus a determined 80 increment, as hereinafter explained.

The tank 5 is formed as a sealed chamber 80 the connection from which to the feed heater 6 is controlled by a manually regulatable spring-loaded valve 10, the said connection extending through the feed heater 6 to the feed pump 11.

12 denotes a Venturi-meter which serves to measure the total quantity of condensate passing through the piping 7 to the feed heater 6. To ascertain the quantity of steam condensed in the condenser, there is subtracted from the quantity measured by the meter the calculated quantity of steam used in operating both stages 16, 16' of the ejector air pump, the primary stage 16 of 90 which is connected by a valved pipe 16' with 95 the condenser 1.

Steam from the primary stage 16 condensed in the jet condenser 18 connected with the tank 5 by the valved pipe 18' passes with the injection water by way of the connection 100 19 to the collector box 2 and into the closed circulation system, the connection 19 having a return bend with a valved branch or air passage 19' leading to the condenser 1. Steam from the secondary stage 16' passes 105 with the air by way of the pipe 17 to the feed heater 6 which also functions as a surface condenser having a vent 20 and a drain

connection 21 leading to a tank 22 fitted with said heater at any convenient location without necessity for providing a substantial static head.

The tank 5 has an air vent controlled by a valve 14 permitting discharge of air from the closed system. 2. In a surface condenser installation, in combination, a main condenser, a collecting box connected to said condenser, a tank

15 denotes a normally closed thermostatic valve for by-passing overheated water from the feed heater 6 to the condenser 1 by way 10 of the connection 15'. 35

For convenience of illustration the tank 5 is shown as being at a considerable elevation:

What I claim is:—

15 1. In a surface condenser installation, in combination, a main condenser, a collecting box connected to said condenser, a tank, a condensate pump having its inlet connected to said box and its outlet connected to said 20 tank, an equalizing pipe for returning part of the condensate from said tank to said box, a float valve controlling the passage of condensate from said tank to said box, and maintaining a constant level in said box, a feed supply, a feed heater, and a connection 25 from said tank to said feed supply by way of said heater, said tank being formed as a sealed chamber so that said condensate pump creates an artificial head in said connection, 30 permitting location of said feed supply and

30 forming as a sealed chamber, a condensate pump having its inlet connected to said box and its outlet connected to said tank, an equalizing pipe connecting said tank and 40 said box, a float valve controlling the passage of condensate from said tank to said box for maintaining a constant level in said box, a feed supply, a feed heater, an ejector air pump having connections with said condenser, with said tank, with said box and with said heater, a connection from said tank to said feed supply by way of said heater, and a measuring device incorporated in said connection, serving to measure the 50 total quantity of condensate passing to said heater. 45

In testimony whereof I have signed my name to this specification in the presence of two subscribing witnesses.

W. A. DEXTER.
